UNITED STATES PATENT OFFICE.

OSCAR L. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

THREAD-BOARD LIFTER.

1,151,384.

Specification of Letters Patent. Patented Aug. 24, 1915.

Application filed October 31, 1910. Serial No. 589,920.

To all whom it may concern:

Be it known that I, OSCAR L. OWEN, a citizen of the United States of America, residing at Whitinsville, in the county of Worcester and State of Massachusetts, have invented certain new and useful Improvements in Thread-Board Lifters, of which the following is a full, true, and concise specification.

The invention consists in an improved means for counterbalancing the thread-board rails or thread-guide supports of spinning frames so that they can be easily lifted or turned up for doffing and will remain lifted until intentionally replaced.

The object of the invention is more especially to provide such counterbalancing means with provisions whereby the counterpoising part will change its relation to the fulcrum of the lifter lever, so that it will be ineffective to raise the rail when the latter is in its normal or horizontal position, but yet will sustain the weight thereof when the same has been lifted, and cushion its return to normal position, and also to permit adjustment of the lifting moment of the lever to serve rails or thread-guide supports of different lengths and weights, or rails having different types of thread guides or other attachments supported by them.

Referring to the drawings, Figure 1 is a perspective view of a portion of a spinning frame showing the thread-board rail equipped with an embodiment of this invention and also showing the spindles; Fig. 2 is a transverse sectional view of the roller-beam and thread-board rail indicating the operation of the invention. Fig. 3 is a top plan view of the lifter lever unmouted and the shifting counterpoise. Figs. 4 and 5 illustrate transverse sectional views of a modified form; Fig. 6 a detail of the construction thereof.

The thread-board rail 1 in the present instance is formed of metal having a flat top plate and a rear flange 1^a like an ordinary angle-iron bar and is hinged to the front edge or face of the roller-beam 2 by means of several hinges 3 so that it can swing as shown in Fig. 2, suitable supports being provided on the roller-beam for sustaining it in horizontal or working position. The roller-beam 2, it will be understood, extends from end to end of the spinning frame and the thread-board rail is co-extensive there-

with for substantially its full length, but may be formed in one or more horizontal sections as desired, depending upon convenience and the number of spindles served. At its forward margin the thread-board rail carries the thread-guides 4 which include the usual wire pig-tail guides 5 through which the yarn passes and is guided to the traveler-rings of the spindles in the usual manner and as indicated in Fig. 1. The wire guides are directly over or in alinement with the spindles when the rail is in its working position and the thread-board rail upon which the guides are mounted is thus so close to the plane of the spindles that convenience of access to the latter requires that the rail and attached parts be turned upwardly and out of the way when it is desired to doff the spindles, and at such time it is desirable that the rail shall, of its own accord, remain in its elevated or lifted position until replaced in its horizontal or working position by the attendant, and that the return can be effected by the attendant at any point along the length of the rail, without requiring the operation of any latches or locking devices. The present invention utilizes a shifting weight or counterpoise as a simple and effective means of accomplishing these and other desirable objects.

On the front face flange of the roller-beam 2 and below the level of the thread-board rail, there is bolted a bracket 6, which is preferably provided with oblong bolt-holes, as shown at 7 in Fig. 1, so that its position on the beam can be adjusted. The pin 8 carried in the forwardly projecting ears of this bracket 6 constitutes the fulcrum for the lifter-lever 9 by which the counterbalancing effect is imparted to the thread-board rail. The forward arm of the lifter-lever extends outwardly and upwardly from the fulcrum toward the under side of the thread-board rail where it is adapted to engage, either directly with the under surface of the rail, as later described, or with a suitable bearing-plate or block 10, secured thereto, or with some other connecting part controlling the swinging movement of the rail and guides. The other arm of the lifter-lever 9 extends inwardly from the fulcrum 8, under the roller-beam and forms the support for the shifting counterpoise 11 which in the present instance is a rolling

weight adapted to roll on the lever toward and from its fulcrum and thus vary its lifting movement. When the thread-board rail is moved into its working position, indicated 5 in full lines in Fig. 2, the inward arm of the lever is caused to incline upwardly so that the counterpoise 11 rolls by gravity toward the fulcrum of the lever, to a position where its effective leverage is insufficient to 10 over-balance the opposing weight or pressure of the thread-board rail and its attached parts upon the end of the outer arm of the lever, but when the rail is turned or lifted to its raised position such as indicated 15 by the dotted lines in the same figure, the pressure on the outer arm of the lever is released and the inward arm falls, under the weight of the counterpoise, to the dotted line position of downward inclination and 20 the counterpoise thereupon rolls toward the opposite end, increasing its leverage, so that if now the thread-board rail is released, the pressure it will exert on the outer arm of the lever will not be sufficient to restore the 25 lever to its former position. The rail will thus be held lifted until sufficient additional pressure is brought to bear, as by the hand of the attendant, to restore the arm to its upwardly inclined position and the counterpoise to its position of least leverage effect. 30 As the return of the rail must be made against the weight of the counterpoise, and as the inertia of the latter compels it to take up its rolling motion rather slowly, it will 35 be evident that slamming of the thread-board rail and consequent disarrangement of the thread guides or injury to the rail is rendered impossible. In the present instance, the end of the outer arm of the 40 lifter lever is provided with a rounded nose or tip which is adapted to slide on the under side of the thread-board rail or the bearing plate 10 thereof, as the lever swings on its fulcrum.

45 As shown in Figs. 1 and 2, the bearing plate 10 is provided with a lug or stop 12 which limits the sliding movement of the end of the lever and thereby stops the upward movement of the thread-board rail 50 before it reaches a vertical or rearwardly inclined position, so that the thread guides 5 are thus prevented from swinging backwardly over the roller-beam, where they might strike or interfere with the delivery 55 rolls, and just in front of the lug the bearing plate is provided with a notch or seat indicated at 13 in Fig. 2, which retains the tip of the lever in engagement with the stop, preventing recoil therefrom and prescribing 60 a definite lifted position for the rail.

Any form of shifting or rolling counterpoise will be suitable to effect the variation in the lifting moment of the lever, provided it is adapted to move easily and freely on 65 its support. The form of counterpoise

shown in the drawings is particularly desirable, however, since it can be made with any desired mass sufficient to counterbalance a long and heavy thread-board rail or section thereof, without encroaching on the 70 space within the spinning-frame devoted to other parts thereof. This counterpoise consists of a body of metal having its longest dimension disposed lengthwise of the roller beam and centrally divided by a 75 deep annular groove 11^a so that it will fit saddle-fashion on the lifter lever, resting and rolling thereon by its central waist portion or reduced diameter. The front flange of the roller beam 2 serves to stop the motion of the shifting counterpoise when it rolls toward the fulcrum and its motion away from the fulcrum is stopped by an abutment 14 which has a cushion face 15. 80 This abutment is adapted to be adjusted longitudinally on the lever so that the maximum distance of the counterpoise from the fulcrum can be varied when necessary to increase or diminish the moment of the lever in accordance with the weight of the 85 thread-board rail to be sustained. One or several lifter levers may be used for each rail, the adjustable stops thereon being set so that the rail will be just sufficiently overbalanced, when lifted, to be maintained 90 safely in that position, and sufficiently counterbalanced, when horizontal, to be lifted easily.

In Figs. 4 and 5 the construction is the same as that previously described except for the connection between the lever and the thread-board rail. In this modified form the outer arm of the lifter lever 9 bears directly against the under side of the angle-iron form of thread-board rail, and the rear flange 1^a of the latter serves as the abutment stop by which the sliding motion of the lever thereon is limited, and the rail sustained in a prescribed lifted position. The rounded end of the lever is adapted to enter a detent recess 17, like the recess in the bearing plate 10, and when in this position a finger 16 on the side of the arm engages the rear flange 1^a to limit the sliding movement, as clearly shown in the drawings. The detent recess 17 is a shallow groove 17 milled out of the under side of the thread-board rail, as shown in Fig. 6.

It will be understood that it is within the range of ordinary mechanical variation to substitute a tension spring for the force of gravity in the device above described.

I claim as my invention the following:

1. A thread-board lifter for spinning frames comprising a lifter-lever fulcrumed beneath the thread-board rail with one of its arms arranged to lift the rail and the other extended inwardly therefrom, and a shifting counterpoise carried by the inward arm and normally capable of moving along 125 130

the lever arm to vary the lifting moment of the lever and by reason of its inertia to prevent slamming of the thread-board.

2. A thread-board lifter for spinning frames comprising a lifter-lever fulcrumed beneath the thread-board rail, a counterpoise normally shiftable on the lever to vary the lifting moment thereof and by reason of its inertia to prevent slamming of the thread-board, and an adjustable stop for limiting the extent of shifting movement of the counterpoise.

3. A thread-board lifter for spinning frames comprising a hinged thread-board rail, and a lifter-lever engaged therewith, in combination with a shifting counterpoise on the said lever movable thereon by the movement of the rail, from a position in which it overbalances the pressure of the rail to a position in which such pressure overbalances it.
4. The combination of a thread-board rail

for spinning machines, a lifter-lever engaged therewith, a cylindrical weight having a peripheral groove midway between its ends for engaging the lever and a stop adjustably mounted on the lever for limiting the motion of the weight along the lever.

5. The combination of a thread-board rail for spinning machines, a lifter-lever engaged therewith, and a rolling weight mounted on the lever, the radius of the rolling surface of said weight being less than the distance from the axis to the outer portion of the weight.

In testimony whereof, I have signed this specification in the presence of two witnesses.

OSCAR L. OWEN.
